UNITED STATES PATENT OFFICE

PHILIP F. WELLS, OF MILFORD, MICHIGAN.

WHEEL-CULTIVATOR.

SPECIFICATION forming part of Letters Patent No. 252,637, dated January 24, 1882.

Application filed November 10, 1879.

To all whom it may concern:

Be it known that I, PHILIP F. WELLS, of Milford, in the county of Oakland, and in the State of Michigan, have invented certain new and useful Improvements in Frames for Wheel-Cultivators; and I do hereby declare that the following is a full, clear, and exact description thereof, reference being had to the accompanying drawings, and to the letters of reference marked thereon, making a part of this specification.

The nature of my invention consists in the peculiar construction of a wrought-iron frame for wheel-cultivators, and in the combination, with this frame, of the draft or draw rods and lateral braces, as will be hereinafter more fully set forth.

In the annexed drawings, Figure 1 is a perspective view of a wheel-cultivator embodying my invention. Figs. 2 and 3 are detailed views of parts thereof.

The main part of the frame consists of only two pieces, A and B, of iron united by bolts at the outside rear corners. The front part, 25 A, is bent nearly at right angles on each side, the bent sides extending back parallel to each other at the right width to attach the front outside standards, C C, until they pass the cross-piece D, which sustains the rear end of 30 the tongue F. They are then bent outward to the right width to attach the outside back standards, C'. This rear piece is provided with the two converging portions g, the two straight transverse portions h, and the two 35 parallel longitudinal portions l. The converging portions brace the handles, the transverse portions provide bearing for the shovel-standards C², and the parallel longitudinal portions form the deep central recess, L, into which the 40 operator may step as he handles lever J. The rear piece, B, is of the peculiar form shown, so as to perform three functions, viz: It acts as a lateral brace to hold the outside part of the frame and standards C' C' rigidly in their 45 positions. It also holds the rear center standards, C² C², and strengthens the cross-bar D. Its peculiar form also enables the operator to step into the rear end of the tongue, and thus more easily handle the lever which raises and 50 lowers the cultivator. The front part of the frame is strengthened by bending the front, as shown at A', and then attaching a straight piece

of iron, G, by the bolts a, by which the draw-rods b are attached, separating them by washers or other device in the center and bringing them together at their ends, thus forming what I call a "truss-front." The tongue and draft-bar are both attached to this front. Also, all of the draw-rods are attached to it or near it, so that the whole forward strain may be concentrated here. All the standards are braced in a lateral direction by braces d, and the rear center standards, C², may be spread by changing their braces so as to straddle the rows of corn when the center standard, C³, is removed.

H is the cranked axle, provided with the wheels I I and operated by the lever J.

I am aware that prior to my invention various forms of mechanism have been devised having the same general end in view proposed by me. I therefore restrict my improvements to the combinations of specific parts set forth in the following claims.

Having thus fully described my invention, what I claim as new, and desire to secure by Letters Patent, is—

1. In a wheel-cultivator, the combination, with the handle or lever J, of the cultivator-frame consisting of the front and side bars, A' A A, the separate rear bar, B, the latter provided with inclined portions g g, and connected to the cross-bar D by a rectangular portion formed with the sides l l, thereby constituting the deep recess L between the side bars, A A, and the central standards, substantially as set forth.

2. The wheel-cultivator frame composed of the two pieces A and B and cross-bars D and G, the said pieces A B bent substantially as shown and described; and for the purposes set forth.

3. The combination of the frame A B, constructed as described, the front bar, G, the plow-standards, the draw-rods b, and lateral braces d, substantially as and for the purposes herein set forth.

In testimony that I claim the foregoing I have hereunto set my hand this 13th day of September, 1879.

PHILIP F. WELLS.
